UNITED STATES PATENT OFFICE.

LÉON NICOLAS BRILLOUIN, OF PARIS, FRANCE.

TELEPHONE AND WIRELESS-TELEGRAPHY INSTALLATION.

1,404,574.

Specification of Letters Patent. Patented Jan. 24, 1922.

Application filed April 25, 1918. Serial No. 230,795.

To all whom it may concern:

Be it known that I, LÉON NICOLAS BRILLOUIN, citizen of the French Republic, residing at Paris, France, have invented certain new and useful Improvements in Telephone and Wireless-Telegraphy Installations, of which the following is a specification.

This invention relates to telephone and telegraph installations and more particularly to wireless telegraphy, which form the subject of the United States patent application No. 174,633 filed on the 13th June 1917 by Brillouin and Beauvais which mainly consists in inserting a condenser into each of the connections of the electrodes to each other, and using as an amplifier at the receiving stations of such installations, a number of audions or repeaters each comprising a filament heated by an electric current and two different electrodes, and in connecting the second electrode or plate of one audion to the first electrode or grid of the next audion, and the first electrode or grid of the first audion to the line, in connecting moreover the second electrodes or plates of each audion by means of a resistance to one of the poles of a source of current.

The invention has for its main object to arrange such installations so as to avoid the production of internal resonance, and so as to ensure amplification of any waves which they receive, whatever be their length, with or without heterodyning. The heterodyning can occur when the receiving apparatus is almost synchronized for the lengths of external sustained waves to be received. Such external sustained waves then generate in the apparatus internal waves which are almost synchronized with the external waves. The combined effects of the external waves and the internal waves produce beats such as are produced in a heterodyne system. These beats are audible in the telephone.

The invention mainly consists in connecting, by means of a suitable capacity, the first electrode or the grid of the first audion of such installations to the second electrode or the plate of another suitably selected audion.

The invention comprises other arrangements, more particularly referred to herein-after.

In the accompanying drawing, by way of example:

Fig. 1 shows diagrammatically a wireless telegraphy receiving station arranged in ac-

cordance with a first method of carrying out the invention;

Fig. 2 shows diagrammatically a wireless telegraphy receiving station arranged in accordance with a second method of carrying out the invention.

First of all, and in accordance with the application hereinbefore referred to, a number of audions a^1, a^2, a^3, a^4 , is taken each comprising a filament 10, 20, 30, 40, a first electrode or grid 100, 200, 300, 400 next to the filament and a second electrode or plate 1, 2, 3, 4, separated from the filament by the "grid".

A source of electricity, for instance a battery b , is taken, intended to supply the current for heating the filaments 10, 20, 30, 40 of the audions a^1, a^2, a^3, a^4 , and the said filaments are connected to the terminals of the said source of electricity, the connection being in parallel.

Another source of electricity c is provided, intended to give a tension V in the plates 1, 2, 3, 4. One of the terminals of the said source c is connected to the terminal of opposite sign of the source of electricity b , and the plates 1, 2, 3, 4 are connected to the other pole of the said source of electricity c , a resistance d^1, d^2, d^3 being inserted between said other pole and each of the said plates, with the exception of that of the last audion.

One of the receiving terminals e^1 of the installation which is adapted to be connected to any known form of radio receiver is connected to that pole of the source b , which is connected to the source c , and the other receiving terminal e^2 , which is adapted to be connected to the other terminal of the radio receiver, is connected to the grid 100 of the first audion, a condenser f^1 being preferably inserted between the said terminal and the said grid.

The plate 1 of the first audion is connected to the grid 200 of the second audion, a condenser f^2 being inserted between the said plate and grid. Identical connections are made between the plates and the grids of the next audions.

The resistance inserted between the plate 4 of the the last audion, and the source of electricity c , is replaced by a telephone instrument g .

Each grid is then connected, by means of a resistance h^1, h^2, h^3, h^4 either to the source of current b or, still better, to a potentiometer j shunted across the terminals of

a source of current k , one of the terminals of which is connected to one of the terminals, preferably to the positive terminal, of the source of current b .

5 Nevertheless, care must be taken, when connecting such an installation, to avoid creation of any reaction capacity that acts on any other element than the grid of the first audion. It is therefore advisable not 10 only to avoid any auxiliary connection that may produce such capacities, but also to avoid their production by the connection itself, for instance owing to proximity of connection wires, studs or terminals.

15 For that reason, all the audions are preferably arranged in line, in order, all the connections being grouped against the audions.

According to the invention, for the purpose of increasing the amplifying effect of 20 the installation, the grid 100 of the first audion is then connected by means of a capacity l^1 to a plate such as the plate 2, 3 or 4 of one of the following audions.

25 The capacity l^1 is preferably arranged, so that its value may be modified at will, and also so that it may be connected, according to circumstances to the plate of any one of the audions a^2 , a^3 , a^4 .

30 It is necessary to point out that when the value of the capacity l^1 is increased, there is first produced an increase of the amplification, then heterodyning, and that by regulating the capacity l^1 regulation of the 35 apparatus may be effected in a very simple manner.

It is however impossible to select any audion, the plate of which is to be connected by the capacity l^1 to the grid 100 of the 40 first audion. If the audion is wrongly selected, either heterodyning does not take place, or the heterodyning takes place with a certain delay and suddenly and it is necessary subsequently to reduce the value 45 of the capacity l^1 considerably in order to stop the heterodyning.

On the contrary, if the audion is properly selected, the heterodyning takes place gradually and without delay, and it ceases to take 50 place as soon as the capacity l^1 is brought to a value slightly below that for which the heterodyning began to take place.

For the choice of the audion, it must be pointed out that a given audion does not 55 ensure heterodyning for wave lengths smaller than a given wave length, and that for wave lengths exceeding a given value, the heterodyning takes place suddenly and with a delay.

60 It is therefore necessary to choose the audion in accordance with the length of wave to be received, bearing in mind that as the lengths of wave increase, it is necessary to take the audions in an order depending on their order number, and also on the

fact whether this order number is an even or an odd number.

It is advisable to choose suitably, on the one hand, the resistance h which connects the grid of the audion to the installation, 70 the plate of which is connected by the capacity l^1 to the grid of the first audion, and also the capacity f which connects the said grid to the plate of the preceding audion. In fact, if the resistance and this 75 capacity are too small, amplification is lost, and if they are too large, there will be a singing sound in the amplifier.

For the purpose of reducing adjustments and avoiding modification, according to the 80 lengths of waves, of the connections of the capacity l^1 , the said capacity l^1 is connected to the plate of the last audion (a^4 in the construction shown in Fig. 2), and in addition are used the following arrangements; 85

Between the terminals of the telephone g which is inserted between the plate of the last audion and the positive pole of the high voltage source of electricity c —the said telephone may be moreover replaced 90 either by the primary of a transformer, the secondary of which is connected to the telephone, or by any desired suitable measuring instrument—is inserted a capacity g^1 and between the plate of the last 95 audion and the telephone g —or its substitute—is inserted a resistance g^2 and a suitable self-inductance coil g^3 .

In this way it is possible to produce heterodyning for any desired lengths of 100 sustained waves, from the smallest to the largest.

Obviously the invention is not limited to the methods indicated, but comprises any modifications within the scope of the claims. 105

I claim as my invention:—

1. A wireless receiving system comprising receiver terminals, an amplifier embodying a series of audions each comprising a filament, a grid, and a plate, circuits connecting the grid of the first audion to one of the receiver terminals and connecting the grids of the other audions to the respective plates of the preceding audions in the series, and a suitable capacity connecting the grid of the first 110 audion to the plate of another audion of the series.

2. A wireless receiving system comprising receiver terminals, an amplifier embodying a series of audions each embodying a filament, 115 a grid, and a plate, a circuit connecting the grid of the first audion to one of the receiver terminals, circuits connecting the grids of other audions to the respective plates of the preceding audions in the series, and a variable capacity connecting the grid of the first audion to the plate of another audion of the series.

3. A wireless receiving system comprising receiver terminals, a series of audions each 120

comprising a filament, a grid and a plate, a circuit connecting the grid of the first audion to one of the receiver terminals, circuits connecting the grids of the other audions to the 5 respective plates of the preceding audions in the series, and a suitable capacity adapted to connect the grid of the first audion to the plate of another audion of the series.

4. A wireless receiving system comprising 10 receiver terminals, a series of audions each comprising a filament, a grid and a plate, a circuit connecting the grid of the first audion to one of the receiver terminals, circuits connecting the grids of the other audions to the 15 respective plates of the preceding audions in the series, and a variable capacity connecting the grid of the first audion to the plate of another audion of the series, the latter audion being so selected that heterodyning 20 takes place gradually and with delay and ceases when the capacity is reduced to a value slightly below that at which hetero- dyning commences.

5. A wireless receiving system comprising 25 receiver terminals, a series of audions each comprising a filament, a grid, and a plate, a circuit connecting the grid of the first audion to one of the receiver terminals, a source of current supply for the filaments of the 30 audions, another source of current supply of given voltage, resistances connecting the latter source of current supply to the plates of the audions, a circuit connecting the grid of the first audion to one of the receiver terminals, circuits connecting the grids of the other audions to the respective plates of the preceding audions in the series, and a suitable capacity connecting the grid of the first audion to the plate of another audion of the 35 series.

6. A wireless receiving system comprising receiver terminals, a series of audions each

embodying a filament, a grid, and a plate, a source of current supply connected to the filaments of the audions, another source of 45 current supply, resistances connecting the latter source of current supply to the respective grids of the audions, a circuit connecting the grid of the first audion to one of the receiver terminals, circuits connecting the 50 grids of the other audions to the plates of the preceding audions, and a capacity connecting the grid of the first audion to a plate of another audion of the series, the said resistance and the capacity being of such relative value that they will avoid reduction of amplification and will also prevent singing.

7. A wireless receiving system comprising receiver terminals, a series of audions each comprising a filament, a grid, and a plate, a 60 source of current supply connected to the filaments of the audions, another source of current supply, resistances connecting the latter source of current supply to the grids of the audions, the grid of the first audion 65 being connected to one of the receiver terminals, circuits connecting the grids of the other audions to the plates of the preceding audions in the series, a capacity connecting the grid of the first audion to the plate of the 70 last audion in the series, and a telephone circuit connected to the plate of the last audion, said telephone circuit containing a resistance and a self inductance coil in series with the telephone, and also containing a 75 capacity which shunts the telephone.

In testimony whereof I have hereunto set my hand in presence of two subscribing witnesses.
